GUARD PIN

Edward C. Manchester, Attleboro, Mass., assignor
to Walter W. Ross and Company, Inc., Kansas
City, Mo., a corporation of Missouri

Application October 25, 1950, Serial No. 12,716

Term of patent 14 years

(Cl. D29—2)

To all whom it may concern:

Be it known that I, Edward C. Manchester, a citizen of the United States, residing at Attleboro, in the county of Bristol and State of Massachusetts, have invented a new, original, and ornamental Design for a Guard Pin, of which the following is a specification, reference being had to the accompanying drawing forming a part thereof.

Fig. 1 is a front elevational view of a guard pin, showing my new design; and,

Fig. 2 is a side elevational view of the guard pin.

The lettering shown in dotted lines in Fig. 1 is for illustrative purposes only. The characteristic

features of the design illustrated in Fig. 2 are shown in full lines.

I claim:

The ornamental design for a guard pin, as shown and described.

EDWARD C. MANCHESTER.
